UNITED STATES PATENT OFFICE.

EDWARD T. PRINDLE, OF AURORA, ILLINOIS.

DESIGN FOR A WHEEL FOR CARPET-SWEEPERS.

SPECIFICATION forming part of Design No. 16,480, dated January 19, 1886.

Application filed August 22, 1885. Serial No. 175,115. Term of patent 14 years.

To all whom it may concern:

Be it known that I, EDWARD T. PRINDLE, of Aurora, in the county of Kane and State of Illinois, have invented and produced a certain new and original Design for the Wheels of Carpet-Sweepers; and I do hereby declare that the following is a full, clear, and exact description of the invention, which will enable others skilled in the art to which it appertains to make and use the same, reference being had to the accompanying drawings, and to letters of reference marked thereon, which form a part of this specification.

Figure 1 is an end view of a carpet-sweeper, displaying thereon in their appropriate place two of my newly-designed traction-wheels. Fig. 2 is a top view of the same, and Fig. 3 an edge view of my newly-designed wheel.

The peculiar characteristics of my design consist in the rounded or convex periphery, as viewed edgewise of the wheel, and in a circle of gear-teeth on the side of the wheel projecting out from the plane of the side, the circle of such gear being less than that of the convex periphery, but yet concentric with it.

A and B each represents a wheel showing my new design. The rounded periphery or tire is seen at *e*, and on the side or face of the wheel is the raised circle of gear-teeth *f*. This circle of teeth is concentric with the periphery or larger circle *e*, but has a smaller diameter. The periphery *e* and the circle described by the teeth *f* are thus in different planes.

The wheel C need not be here described, as my present application is confined to the wheel above described. It is shown in its relation or position to wheels like A B on the end of a carpet sweeper, as previously mentioned.

I claim—

The design for a wheel suitable for carpet-sweepers and other articles, the same consisting of a wheel, A, having a rounded or convex edge or periphery, *e*, and the circle *f* of teeth on its side, such circle being of lesser diameter than but concentric with the main body of the wheel, as shown and described.

EDWARD T. PRINDLE.
